CLAIM

The ornamental design for a display screen or portion thereof with graphical user interface, as shown and described.

DESCRIPTION

The sole FIGURE is a perspective view of a display screen or portion thereof with graphical user interface.

The outermost broken lines show the environment and form no part of the claimed design. The inner broken line rectangle shows the display screen or portion thereof and forms no part of the claim design. The remaining broken lines and show portions of the graphical user interface that form no part of the claimed design.

1 Claim, 1 Drawing Sheet
